UNITED STATES PATENT OFFICE

2,368,766

RAILWAY SWITCH CONTROLLING APPARATUS

Ronald A. McCann, Swissvale, Pa., assignor to
The Union Switch & Signal Company, Swiss-
vale, Pa., a corporation of Pennsylvania

Application April 3, 1943, Serial No. 481,715

11 Claims. (Cl. 246—134)

My invention relates to railway switch controlling apparatus, and particularly to emergency control apparatus for at times effecting operation of a switch.

In power operated switch control apparatus, the control circuits which regularly effect operation of a switch between its normal and reverse positions are commonly controlled in part by a relay which is known as a switch locking relay. The switch locking relay is in turn controlled in part by one or more traffic responsive relays so as to be normally energized but to become de-energized in response to the presence of a train. In an emergency, it is sometimes desirable to effect operation of a track switch even though its switch locking relay is deenergized.

One feature of my invention is the provision of novel and improved means for effecting operation of a switch in such an emergency, in which it is necessary to operate the emergency release apparatus for each operation of a switch between its normal and reverse positions.

Another feature of my invention is in the means provided to prevent the regular control circuits from becoming closed during emergency control of the switch.

I shall describe one form of apparatus embodying my invention, and shall then point out the novel features thereof in claims.

The accompanying drawing is a diagrammatic view showing one form of apparatus embodying my invention, in which a push-pull circuit controller is used for controlling an emergency release stick relay and a time element device for arranging emergency control circuits for effecting operation of a pair of track switches in a crossover.

Referring to the drawing, a track plan is shown in Fig. 1a, in which two parallel tracks are interconnected by a crossover through switches designated by the reference characters A! and B!. In order to simplify the drawing, each track, comprising two parallel series of track rails, is represented by a single line.

Each of these tracks is divided into sections by insulated joints designated by the reference character 9. The section of track in which switch A! is located is designated by the reference character A!T, and the section in which switch B! is located is designated by the reference character B!T. Each of the sections A!T and B!T is provided with a track circuit including a suitable source of current, such as a battery 10, connected across the rails adjacent one end of the section, and a track relay designated by the reference

character A!R or B!R, respectively, connected across the rails adjacent the opposite end of the section.

Traffic movements in opposite directions over these sections of track are governed by signals designated by the reference characters 2, 4, 6 and 8. These signals may be of any suitable design such, for example, as the searchlight type.

The contacts operated by the various relays and other control devices are identified by numbers, each such number having a distinguishing prefix from which it is separated by a dash when the associated contact is shown apart from the relay or other device by which it is operated, except when the associated contact is shown grouped with another contact of the same relay or other device having a distinguishing prefix. The prefix for each of these contact numbers comprises the reference character for the relay or other device by which the associated contact is operated. For example, contact 1S—22, shown in the upper left-hand portion of the drawing in the control circuits for relay 1VP, is identified by the number 22 which is separated by a dash from the prefix 1S which is the reference character for relay 1S by which this contact is operated. Contacts 34 and 35, operated by the same relay 1S, are shown grouped with contact 1S—22, and therefore the prefix is omitted from these contact numbers.

Switches A! and B! are operable to their normal positions, in which they are shown in the drawing, or to the opposite or reverse positions, by mechanisms designated by the reference characters A!M and B!M, respectively. Mechanisms A!M and B!M are in turn controlled by a polarized switch control relay 1W.

Relay 1W is regularly energized in the normal or the reverse direction by circuits controlled by a switch locking relay 1LS in the energized condition, and by a polarized lever repeater relay 1VP, as well as by other relays by which relay 1VP is also controlled, as will be referred to later.

Relay 1LS has a pick-up and a stick circuit controlled by the traffic responsive track relays A!R and B!R, and by time locking stick relays 2AS, 4AS, 6AS, and 8AS associated with signals 2, 4, 6 and 8, respectively. The pick-up circuit for relay 1LS is also controlled by a normally closed contact 17 of a switch control device 1V here shown as a lever. Relays 2AS, 4AS, 6AS and 8AS may be controlled similarly to relay 2AS shown in Fig. 1F of Letters Patent of the United States No. 2,301,297, granted November 10, 1942,

to Lloyd V. Lewis for Railway traffic controlling apparatus.

Relay 1VP is regularly controlled by relay 1LS and by lever 1V, and may also be controlled by route selector relays 1RE, 1RW, 1ANE, etc., and by exit stick relays 8XS, 2XS, 6XS, etc., as shown, similarly to relay 1WR shown in Fig. 1C of the Lewis patent referred to. Relay 1W also may be controlled by these route selector and exit stick relays as shown. In other forms of interlocking control systems than the one shown in the Lewis patent, relays 1VP and 1W may be controlled by other means instead of by the route selector and exit stick relays. The route selector and exit stick relays may be controlled similarly to such relays shown in Figs. 1A and 1B of the Lewis patent.

In apparatus embodying my invention, relays 1VP and 1W are also controlled by an emergency release stick relay 1S.

Lever 1V has a center position C which it normally occupies, and has N and R control positions to which it may be moved to effect operation of switches A1 and B1 to normal and reverse positions, respectively. Lever 1V also has a latch contact 41 which is normally closed, but which opens during movement of lever 1V to its N or its R position, and which then again closes when lever 1V reaches the N or the R position.

Relay 1S has a pick-up circuit controlled by an emergency release circuit controller, here shown as a push button 1PB, as well as by the time locking stick relays and by a back contact of relay 1LS. Relay 1S also has a stick circuit controlled by contact 41 of lever 1V, by relay 1VP, and by normal and reverse switch indication relays 1NC and 1RC, respectively, as well as by a back contact of relay 1LS.

Push button circuit controller 1PB is of the push-pull type such, for example, as shown in Letters Patent of the United States No. 2,295,301, granted September 8, 1942, to W. E. Smith for Circuit controllers. Controller 1PB is biased to a mid stroke position, and has two normally open contacts 40 and 46. Contact 40 becomes closed when controller 1PB is pushed in, and contact 46 is closed when controller 1PB is pulled out.

A time element device, shown as a relay 1ER, is controlled by a circuit which includes contact 46 of controller 1PB and also a front contact of relay 1S.

A polarized switch indication relay 1P is controlled similarly to relay 1WP described in the Lewis patent, so as to be energized by current of normal polarity when switches A1 and B1 are in their normal positions and to be energized by current of reverse polarity when switches A1 and B1 are in their reverse positions. Normal and reverse switch indication relays 1NC and 1RC, respectively, are controlled by relays 1P and 1W.

Having described, in general, the arrangement and control of the apparatus shown by the accompanying drawing, I shall now describe, in detail, its operation.

As shown by the drawing, all parts are in their normal condition, that is, switches A1 and B1 are in their normal positions; all signals are indicating stop; track sections A1T and B1T are unoccupied; lever 1V is in its center position C; circuit controller 1PB is in its biased mid stroke position; relays A1R, B1R, 1NC, 1LS, 2AS, 4AS, 6AS and 8AS are energized; relay 1P is energized by current of normal polarity; and time element device 1ER, and relays 1VP, 1W, 1RC and 1S, and the

route selector and exit stick relays are de-energized.

The pick-up and stick circuits for switch locking relay 1LS are both closed. The pick-up circuit passes from terminal B of a suitable source of current, through contacts 11, 12, 13 and 14 of relays 8AS, 6AS, 4AS and 2AS, respectively, contacts B1R-15 and A1R-16, winding of relay 1LS, and contact 17 of lever 1V in its C position to terminal O. The stick circuit for relay 1LS is the same as its pickup circuit just traced as far as the winding of relay 1LS, and then passes through the front point of contact 45 of relay 1LS to terminal O.

15 The circuit by which relay 1NC is energized passes from terminal B, through contacts 1P-18 and 19, winding of relay 1NC, and contact 20 of relay 1W to terminal O.

I shall first assume that a leverman arranges 20 for a train to pass signal 2, over switches A1 and B1 reversed, by effecting energization of route selector relay 1RE and exit stick relay 8XS. Relay 1VP therefore becomes energized by its reverse control circuit passing from terminal B, 25 through contact 1LS-21, right-hand portion of the winding of relay 1VP, contacts 23 and 24 of relays 1RE and 8XS, respectively, and contact 25 of relay 1S to terminal O. Relay 1W then becomes energized by its reverse control circuit passing 30 from terminal B, through contact 26 of relay 1VP closed in the reverse or right-hand position, front point of contact 27 of relay 1LS, winding of relay 1W, front point of contact 28 of relay 1LS, contact 29 of relay 1VP in the right-hand position, and contacts 23, 24 and 25 of relays 1RE, 8XS and 1S, respectively, to terminal O.

35 With relay 1W energized in the reverse direction, mechanisms A1M and B1M are energized, for moving switches A1 and B1 to the reverse positions, by a circuit passing from terminal B, through contact 1W-30, contact 31 of relay 1W closed in the right-hand position, and mechanisms A1M and B1M to terminal O.

40 Upon the completion of the operation of switches A1 and B1 to the reverse position, relay 1P will become energized in the reverse direction. Relay 1RC will then become energized by its circuit passing from terminal B, through contact 1P-18, contact 19 of relay 1P closed in the right-hand position, winding of relay 1RC, and contact 20 of relay 1W to terminal O.

45 Signal 2 will then be operated to the proceed position, causing relay 2AS to become deenergized similarly to the manner shown in the Lewis patent referred to. Relay 1LS will therefore become de-energized due to the opening of contact 14 of relay 2AS.

50 With relay 1LS deenergized and relay 1P energized in the reverse direction, the reverse stick circuit for relay 1W will become closed, passing from terminal B, through contact 1W-32 and contact 33 of relay 1P closed in the reverse or right-hand position, back points of contacts 34 and 27 of relays 1S and 1LS, respectively, winding of relay 1W, back points of contacts 28 and 35 of relays 1LS and 1S, respectively, and contact 1P-50 closed in the reverse position, to terminal O.

55 I shall now assume that all parts of the apparatus are again returned to the normal condition, and that relay A1R becomes deenergized due to a failure in the track circuit for section A1T such, for example, as due to a broken connection between the track battery 10 and the 60 rails of the section. Contact A1R-16 will there-

fore be open, causing relay ILS to be deenergized. I shall further assume that a leverman attempts to arrange for a train to move past signal 2 over switches $\text{A}1$ and $\text{B}1$ reversed, as before, by effecting energization of route selector relay IRE and exit stick relay 8XS . With relay ILS deenergized, the circuit previously traced for relay IVP is open at contact $\text{ILS}-21$, and hence relay IVP cannot become energized by its regular reverse control circuit previously traced.

The leverman will therefore move lever IV to its R position, and will push circuit controller IPB in to close its contact 40 . Relay IS will therefore become energized by its pick-up circuit passing from terminal B, through contacts 36 , 37 , 38 and 39 of relays 8AS , 6AS , 4AS and 2AS , respectively, contact 40 of circuit controller IPB , winding of relay IS , and the back point of contact 45 of relay ILS to terminal O. Relay IS , upon becoming energized, opens its back contact 25 in the regular control circuits previously traced for relays IVP and IW , thereby preventing energization of these relays by their regular control circuits while the switches are under emergency control.

With relay IS energized, and with lever IV in its R position, relay IVP will become energized by its emergency reverse control circuit passing from terminal B, through contact $\text{IS}-22$, right-hand portion of the winding of relay IVP , and contact 17 of lever IV closed in the R position, to terminal O. Circuit controller IPB may now be released to permit it to return to its mid-stroke position, because the stick circuit for relay IS will be closed, passing from terminal B, through contact 41 of lever IV , contact $\text{IVP}-42$ closed in the right-hand position, contact $\text{IRC}-43$, contact 44 of relay IS , winding of relay IS , and the back point of contact 45 of relay ILS to terminal O.

The leverman will then pull circuit controller IPB out to close its contact 48 and thereby complete an energizing circuit for time element device IER , passing from terminal B, through contacts 36 , 37 , 38 and 39 of relays 8AS , 6AS , 4AS and 2AS , respectively, contact 46 of controller IPB , contact 47 of relay IS , and the winding of device IER to terminal O. It will be necessary for the leverman to hold controller IPB in this position until time element device or relay IER has had time to close its contacts and thereby complete an emergency reverse control circuit for relay IW , passing from terminal B, through contact 26 of relay IVP in the right-hand position, contact 48 of relay IER , front point of contact 34 of relay IS , back point of contact 27 of relay ILS , winding of relay IW , back point of contact 28 of relay ILS , front point of contact 35 of relay IS , contact $\text{IER}-49$, contact 29 of relay IVP closed in the right-hand position, and contact 17 of lever IV closed in the R position to terminal O.

With relay IW thus energized by current of reverse polarity, mechanisms $\text{A}1\text{M}$ and $\text{B}1\text{M}$ will become energized for operating switches $\text{A}1$ and $\text{B}1$ to their reverse positions as previously described. Relay IP will then become energized in the reverse direction, and relay IRC will become energized as previously described. Relay IRC , upon becoming energized, opens its back contact $\text{IRC}-43$, thereby breaking the stick circuit previously traced for relay IS and causing relay IS to become deenergized.

I shall next assume that all parts of the apparatus are again returned to the normal condition, that the track circuit for section $\text{A}1\text{T}$ then fails,

and that again the leverman attempts to effect operation of switches $\text{A}1$ and $\text{B}1$ to the reverse position by means of the emergency control apparatus. I shall further assume that due to some

obstruction, for example, one of the switches does not complete its operation to the reverse position, and that therefore relay IRC does not become energized. I shall also assume that while relay IS is therefore still energized by its stick circuit, 10 the leverman attempts to return switches $\text{A}1$ and $\text{B}1$ to the normal position by merely moving lever IV to its N position. Movement of lever IV to the N position opens contact 41 , deenergizing relay IS . It will therefore be necessary for the leverman to again push circuit controller IPB in to close its contact 40 , as previously described, in order to return switches $\text{A}1$ and $\text{B}1$ to the normal position.

From the foregoing description and the accompanying drawing, it follows that in apparatus embodying my invention, it is necessary to operate the emergency release circuit controller IPB each time an attempt is made to operate a switch to its normal or its reverse position while the switch is under emergency control. Energization of emergency release stick relay IS opens its back contact in the regular control circuits, thus preventing the possibility of a regular control circuit becoming closed while an emergency control circuit is closed.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In railway switch controlling apparatus including a polarized switch control relay for effecting operations of a given switch to normal and reverse positions according as said polarized relay becomes energized by current of normal or reverse polarity respectively, including means 40 for normally effecting a change in energization of said switch control relay only if a switch locking relay controlled by traffic responsive means is energized, the combination comprising, an emergency release stick relay, a manually controllable pick-up circuit for energizing said emergency release stick relay if said switch locking relay is deenergized, a switch control lever having normal and reverse switch control positions, a polarized lever repeater relay, normal and reverse control circuits controlled by a front contact of said emergency release stick relay and by said lever in its normal and reverse control positions for energizing said lever repeater relay by current of normal and reverse polarity respectively, a time 50 element device controlled by a front contact of said emergency release stick relay, and normal and reverse control circuits controlled by said emergency release stick relay in the energized condition and by said time element device upon the lapse of a measured period of time after said time element device becomes energized for energizing said switch control relay by current of normal or reverse polarity if said lever is in its normal or its reverse position respectively.
2. In railway switch controlling apparatus including regular control means for effecting operations of a given switch to normal and reverse positions only if a given switch locking relay controlled by traffic responsive means is energized, including a switch control device having normal 55

and reverse control positions for controlling operations of said switch to its normal and reverse positions, the combination comprising, an emergency release stick relay, a manually controllable pick-up circuit for energizing said emergency release stick relay if said switch locking relay is deenergized, a stick circuit for retaining said emergency release stick relay energized as long as said switch locking relay is deenergized and said switch control device remains in one of its control positions, and emergency control means including a contact of said emergency release stick relay for effecting operations of said given switch while said switch locking relay is deenergized.

3. In railway switch controlling apparatus including regular control means for effecting operations of a given switch to normal and reverse positions only if a given switch locking relay controlled by traffic responsive means is energized, including a switch control device having normal and reverse control positions, the combination comprising, an emergency manual control device operable to a first or a second control position, a pick-up circuit for said emergency release stick relay controlled by a back contact of said switch locking relay and by said emergency manual control device in its first control position, a stick circuit for said emergency release stick relay controlled by a back contact of said switch locking relay for retaining said emergency release stick relay energized if said switch control device is left in one of its control positions, a time element device controlled by a front contact of said emergency release stick relay and by said emergency manual control device in its second control position, and emergency control means controlled by a front contact of said emergency release stick relay and by said time element device for effecting operations of said given switch while said switch locking relay is deenergized.

4. In railway switch controlling apparatus including regular control means for effecting operations of a given switch to normal and reverse positions, the combination comprising, an emergency release stick relay, an emergency control device biased to a normal position but manually operable to a first and a second control position, a pick-up and a stick circuit for energizing said emergency release stick relay under a given traffic condition which prevents the regular control means from effecting operations of said given switch and said pick-up circuit also controlled by said emergency control device in its first control position, a time element device controlled by said emergency control device in its second control position, and emergency control means controlled by a front contact of said emergency release stick relay and by said time element device for effecting operations of said given switch.

5. In railway switch controlling apparatus including a switch locking relay, the combination comprising, a manual switch control device having a neutral position and a normal and a reverse control position, a pick-up and a stick circuit for energizing said switch locking relay under given traffic conditions and the pick-up circuit also controlled by the neutral contact of said manual switch control device, a polarized repeater relay, a manually controllable emergency release contact, normal and reverse control circuits controlled by said manual switch control device in its normal and reverse control positions respectively and each including a front contact of

5 said switch locking relay connected in multiple with said emergency release contact for energizing said polarized repeater relay, and means including said polarized repeater relay for effecting operations of a given switch to normal and reverse positions.

6. In railway switch controlling apparatus including regular control means for effecting operations of a given switch to normal and reverse positions, the combination comprising, an emergency control device biased to a normal position but manually operable to a first and a second control position, emergency control contact means which becomes closed in response to operation of said emergency control device to its first control position and which remains closed in response to a given traffic condition by which said regular control means is rendered incapable of effecting operations of said given switch, a time contact which 10 becomes closed upon the lapse of a measured period of time in response to operation of said emergency control device to its second control position, and emergency control circuit means controlled by said emergency control contact means and by said time contact for effecting operations of said given switch.

7. In railway switch controlling apparatus including regular control circuit means for effecting operations of a given switch to normal and reverse positions in response to operations of a given regular manual control device to normal and reverse positions respectively, the combination comprising, an emergency control device manually operable to a first and a second control position, an emergency control contact which becomes closed in response to operation of said emergency control device to its first control position and which remains closed if said regular manual control device is left in its normal or its reverse position, a time contact closed upon the lapse of a measured period of time after operation of said emergency control device to its second control position, and emergency control circuit means controlled by said emergency control contact and by said time contact for effecting operations of said given switch.

8. In railway switch controlling apparatus including regular control means for effecting operations of a given switch to normal and reverse positions, the combination comprising, an emergency control device manually operable to a first and a second control position, an emergency control contact which becomes closed in response to operation of said emergency control device to its first control position and which remains closed under a given traffic condition which renders said regular control means incapable of effecting operations of said given switch, and emergency control circuit means controlled by said emergency control contact and by operation of said emergency control device to its second control position for effecting operations of said given switch.

9. In railway switch controlling apparatus including regular control circuit means for effecting operations of a given switch to normal and reverse positions in response to operations of a given manual switch control device to normal and reverse positions respectively, the combination comprising, an emergency control device manually operable to a first and a second control position, an emergency control contact device which becomes closed in response to operations of said emergency control device to its first control position and which remains closed if said given man-

ual switch control device is operated to its normal or its reverse position and left in such position, and emergency control circuit means controlled by said emergency control contact device and by operation of said emergency control device to its second control position as well as by said given manual switch control device for effecting operations of said given switch.

10. In railway switch controlling apparatus including a switch control device manually operable to a normal and a reverse position, the combination comprising, a polarized repeater relay for said switch control device, a traffic responsive relay energized under given traffic conditions but which becomes deenergized under other traffic conditions, an emergency control device manually operable to a first and a second control position, an emergency stick relay which becomes energized in response to operation of said emergency control device to its first control position and which remains energized if said switch control device is left in one of its control positions, normal and reverse circuits for energizing said repeater relay controlled by said switch control device in its normal and reverse positions respectively and also controlled by a front contact of said traffic responsive relay connected in multiple with a front contact of said emergency stick relay, circuits controlled by said repeater relay for effecting operations of

5 a given track switch if said traffic responsive relay is energized, and emergency circuits controlled by said repeater relay and by a front contact of said emergency stick relay and also controlled by operation of said emergency control device to its second control position for effecting operations of said given switch if said traffic responsive relay is deenergized.

11. In railway switch controlling apparatus, the combination comprising, an emergency control device manually operable to a first and a second control position, an emergency stick relay which becomes energized in response to operation of said emergency control device to its first control position under a given traffic condition which prevents regular control circuits from effecting operations of a given switch and which then remains energized under said given traffic condition, regular control circuits controlled in part 15 by a back contact of said emergency stick relay for effecting operations of said given switch to its normal and reverse positions, and emergency control circuits controlled in part by a front contact of said emergency stick relay and 20 by operation of said emergency control device to its second control position for effecting operations of said given track switch under said given traffic condition.
